UNITED STATES PATENT OFFICE.

JUSTUS BISSING, OF HAYS CITY, KANSAS.

VALVE-OPERATING MECHANISM.

SPECIFICATION forming part of Letters Patent No. 726,622, dated April 28, 1903.

Application filed May 7, 1902. Serial No. 106,310. (No model.)

To all whom it may concern:

Be it known that I, JUSTUS BISSING, a citizen of the United States, residing at Hays City, in the county of Ellis and State of Kansas, 5 have invented a new and useful Valve-Operating Mechanism, of which the following is a specification.

My invention relates to certain improvements in steam-engines, and has for its principal object to construct an improved form of valve-operating mechanism with a view of varying the point of cut-off in accordance with the speed and load.

A further object of the invention is to provide for the return of the steam-controlling valve to closed position after each operation by connecting said valve to devices operable by the pressure of steam and to provide for the gradual closing of the valve without shock 20 or jar.

A still further object is to provide each steam-valve with an improved form of regulating mechanism operable by a governor of ordinary construction.

25 A still further object of the invention is to provide an improved form of valve and valve-operating mechanisms particularly adapted for use in connection with rotary engines of the eccentric-piston type and to so construct 30 and arrange such mechanism that the opening of the valves will be properly timed in accordance with the positions of the movable piston-abutments.

With these and other objects in view the 35 invention consists in the novel construction and arrangement of parts hereinafter described, illustrated in the accompanying drawings, and particularly pointed out in the appended claims.

40 In the drawings, Figure 1 is an end elevation illustrating a form of rotary engine provided with valve operating and governing mechanism in accordance with my invention. Fig. 2 is a transverse sectional elevation 45 through the steam-chest and cylinder, illustrating the general arrangement of the steam-chest and the inlet and reversing valves. Fig. 3 is an end elevation illustrating a portion of one of the valve-operating mechanisms drawn 50 to an enlarged scale. Fig. 4 is a plan view of the same, the steam-chest being shown in section. Fig. 5 is a longitudinal sectional ele-

vation of a portion of the valve mechanism on the line 5 5 of Fig. 4.

Similar numerals of reference are employed 55 to indicate corresponding parts throughout the several figures of the drawings.

The rotary engine illustrated in the drawings is one of the usual eccentric-piston type, including the cylinder 10, a shaft 11, and a 60 rotary piston 12, having movable abutments 13. The steam-chest 14, to which steam is supplied through a pipe 15, is divided into upper and lower chambers 16 and 17, communication between said chambers being governed by the 65 steam-inlet valves 18 and 18', located, respectively, in valve-chambers 19 and 19'. From the chamber 17 lead three ports 20, 21, and 22, the ports 21 serving as inlets for the admission of steam to the cylinder 10 and the 70 port 22 being the exhaust-port and in communication with the outer air. In the chamber 17 is a slide-valve 23, having on its upper face a rack 24, intermeshing with an adjusting-pinion 25, said pinion being mounted 75 on a shaft having an operating-handle outside the valve-chest to permit of the adjustment of the slide-valve and direct the flow of steam from the steam-chest to either side of the cylinder and from the other side of said cylinder 80 to the exhaust. This mechanism may be of the class ordinarily employed in rotary engines, the slide-valve being merely employed to permit the reversal of the direction of movement of the engine. The cylinder may 85 be further provided with relief-ports 28, arranged at points in advance of the final exhaust-ports in order to permit the free escape of the steam and prevent back pressure on the movable abutments. The steam-in- 90 let valves are of precisely the same construction and are operated upon alternately to permit the action of the steam on each of the two abutments carried by the rotary piston. If only one abutment is employed, the engine 95 may be readily operated by means of a single valve, and if more than two abutments be employed it is preferred to use an equal number of valves, the operating mechanism being properly timed to successively open said 100 valves as the abutments pass the inlet-ports leading from the lower chamber of the steam-chest to the cylinder. Between the upper and lower chambers 16 and 17 is a steam-

port 30, leading from the substantially cylindrical valve-chamber 19. The valve 18 is carried by a valve-stem 31, the valve being preferably formed by reducing the area of the stem, as shown in Fig. 4. Each of the valve-chambers may be readily formed by boring a circular opening directly through the end portion of the steam-chest, the ends of the opening being covered by plates 33, which 5 may be readily removed to gain access to the valve for examination or repairs. The end 34 of the valve-stem or spindle is of reduced diameter and projects through a suitable opening in one of the plates 33, and at the 10 extreme outer end of said stem is secured a disk 35, on which is loosely mounted the pivot-strap of a rocker-arm 36, the latter being connected by a link 37 to the upper end of a rock-lever 38, to which the corresponding lever of the valve at the opposite end of the steam-chest is likewise connected. The rock-lever 38, as shown in Fig. 1, is pivoted on a stud 39 and is provided at its lower end with an open frame 40, adapted to be operated upon by a cam or eccentric 41, carried by the main shaft 11 of the engine, said cam being so mounted and actuated as to operate alternately on the two valves at opposite ends 15 of the steam-chest.

15 To the valve-stem 31 is secured a disk 42, recessed to form a shoulder 43, with which may engage a hook 45, hung on a pin 47, carried by the arm 37, said hook and shoulder being held in operative relation by a spring 48, carried by the stud 49, which connects the rocker-arm 36 to the link 37. The result of an operative movement of the rock-lever 38 is to cause a partial rotative movement of the valve-stem 31, the rocker-arm 36 rotat- 20 ing on the disk 35 at the end of the valve-stem and the hook 45 being kept in engagement with the shoulder 43 of cam 42. The reversal of this movement would ordinarily move the hook to initial position in readiness 25 for a subsequent operation.

25 Referring to Fig. 1, 50 designates a bracket carried by the cylinder of the engine and serving to support the stem 51 of an ordinary type of governor 52, the latter being rotated from the main shaft 11 through an intermediate belt 53 and the usual belt-wheels and bevel-gears. At the upper end of the bracket 50 is an arm 54, to which is fulcrumed a three-arm lever 55, one end of which is bifurcated and 30 embraces a grooved sleeve, to which vertical movement is imparted by the centrifugal governor. The remaining arms of the lever 55 are connected by levers or rods 56 to adjustable cams 57, the connection being such 35 that said cams will receive simultaneous movement in opposite direction from the governor. Each cam 57 is mounted loosely on the reduced end portion 34 of the valve-stem, and to its periphery is secured a wear-block 58, which may be readily removed and replaced 40 when worn. The contour of the block 58 is governed by the character of the engine and

the work to be performed, its function being to effect the release of the hook 45 from the shoulder 43 of the valve-operating disk at 70 any desired point in the stroke of the engine, the point of cut-off being governed by the vertical movement of the sleeve 56 of the governor. On the lower portion of the hook 45 is secured a stud 60, carrying an antifriction- 75 roller 61, adapted to make contact with the wear-block 58 of the cam, such wear-block being so arranged and proportioned that the contact of the roller therewith will move the hook from engagement with the shoulder 43 80 and cut-off or permit the cutting off of the flow of steam through the inlet-port to the cylinder.

85 At each end of the steam-chest is a segmental chamber 65 in constant communication with the upper chamber 16 of the chest through a suitable port or passage 66, and adjacent to the chamber 65 is a second segmental chamber 66 in communication with the atmosphere. The main stem of the valve 90 extends into both of said chambers and is provided with two vanes or wings 68 and 69, arranged at right angles to each other and disposed, respectively, in the chambers 65 and 67. Both vanes are provided with packing- 95 strips 70, adapted for contact with the curved and side walls of the chamber, an auxiliary packing-strip 71 being introduced between the body of the vane 69 and the valve-stem to prevent the passage of steam from chamber 65 to the atmosphere when the parts are 100 in the position illustrated in 65.

From the lower portion of the chamber 67 extends an opening 72, threaded for the reception of a nipple 73, carrying a valve box 105 or easing 74, in which is a one-way valve 75, adapted to open upwardly when the vanes are moved in the direction of the arrow in Fig. 5, admitting air below the vane 69. From one side of the chamber 74 leads a pipe 110 provided with a regulating-valve 76, which may be opened to a greater or less extent to regulate the speed of the discharge of air from the chamber 67 when the vanes are moved in a direction the reverse of that indicated by the arrow. In the operation of this portion of the device it is to be understood that the vanes 68 and 69 are in the position indicated in Fig. 5 when the valve is closed and the operating mechanism is in the position illustrated in Figs. 3 and 4. When the rock-lever 38 is moved by the eccentric to exert a pulling strain in the direction of the arrow, Fig. 3, the hook 45 being in engagement with the shoulder 43 rotates the disk 125 42 and the valve-stem, opening the valve and permitting the flow of steam through the port 30 and port 20 to the cylinder. The hook is retained in engagement with the shoulder until the roller 61 riding over wear-block 58 releases the hook and shoulder, the degree of opening movement of the valve being governed by the position of the wear-block and the movement of the latter being 130

regulated by the governor. The turning of the valve-stem to open the valve effects a movement of the two vanes 68 and 69 in the direction indicated by the arrow in Fig. 5, 5 the vane 68 moving against the steam-pressure in chamber 65, while the upward movement of the vane 69 induces a flow of air past the valve 75 and into the chamber 67. As soon as the hook is released from the 10 shoulder 43 the steam-pressure exerted on the vane 68 returns the vane to its initial position and closes the valve. This closing movement is resisted by the air in the chamber 67, the downward movement of the vane 15 69 compressing the air and closing the valve 75. As the air can only escape through the valve 76, such air will be compressed to a greater or less extent, depending on the position of the valve, and the vanes will be gradually moved to initial position, the air acting 20 as a cushion to prevent any jar or shock which might be occasioned by the sudden closing of the valve.

The valves at opposite ends of the steam-chest are opened alternately to admit steam to the lower chamber 17 of the valve-chest, successive charges flowing through the same inlet-port to the cylinder and acting successively on the abutments therein.

30 Having thus described my invention, what I claim is—

1. The combination in a steam-engine, of a steam-chest having ports, an oscillating valve for governing the flow of fluid through 35 said ports, an auxiliary chamber in communication with the steam-chest, an oscillating member arranged in said auxiliary chamber and connected to the valve, the axes of oscillation of the valve and movable member being coincident, said member being exposed 40 to steam-pressure, and mechanism for removing the valve to open position against pressure of the steam.

2. In a valve mechanism, a valve, a valve-stem, mechanism connected to the valve-stem for opening the valve, a pair of auxiliary chambers, one in communication with the steam-supply and the other in communication with the outer air, vanes carried by the 50 valve-stem and arranged in said chambers, and means for controlling the flow of air from the air-containing chamber.

3. In a valve mechanism, a valve, a valve-stem, mechanism connected to the valve-stem for moving the valve to open position, a pair 55 of segmental chambers in communication respectively, with the steam-supply and with the outer air, vanes carried by the valve-stem and disposed in said chamber, an air-inlet 60 opening having a one-way valve for admit-

ting air to the air-containing chamber and a regulating-valve for governing the discharge of air from said chamber.

4. In a valve mechanism, a valve, a valve-stem, means connected to the valve-stem for moving the valve to open position, an auxiliary chamber, a vane carried by the valve-stem and arranged within said chamber, a port or passage for placing said chamber in communication with the steam-supply to effect the return movement of the valve to closed position, and means for retarding the closing movement of the valve.

5. In a valve mechanism, the combination with a valve-chamber connected by suitable 75 ports with a source of steam-supply and with a cylinder, a valve arranged within said valve-chamber, means for moving said valve to open position, a casing contiguous to the valve-chamber and divided into two compartments, one compartment connected with a source of steam-supply and the other with an air-supply, vanes mounted within the casing and having fixed connection with the valve and adapted for movement in an arc 80 within said compartments, whereby when the valve is moved to open position the vanes will move therewith admitting air to the air-compartment and exhausting the steam from the steam-compartment, the steam-pressure serving to return the valve to its closed position when released by the opening mechanism and the air in the air-compartment serving to retard the closing movement of the valve, substantially as specified.

6. In a valve-operating mechanism, a ported valve-chamber, a valve disposed in said chamber, a valve-stem, a shouldered disk secured to the valve-stem, a second disk also secured to said stem, a rocker-arm pivotally mounted 100 on the second disk, a link pivotally connected to the outer end of the arm, means for operating the link, a hook pivoted to the link and adapted to engage the shoulder of the first disk, a spring secured to the pivot connecting the rocker-arm and lug and having its free end bearing against the hook, an anti-friction-roller carried at the free end of the hook, and a governor-controlled cam loosely mounted on the valve-stem and adapted to 110 be engaged by the roller to effect the release of the hook from the disk-shoulder.

In testimony that I claim the foregoing as my own I have hereto affixed my signature in the presence of two witnesses.

JUSTUS BISSING.
